Primary Examiner—Stella Reid*Assistant Examiner*—Mark A. Goodwin*(74) Attorney, Agent, or Firm*—Thorpe North & Western, LLP(57) **CLAIM**

The ornamental design for beverage container package, as shown and described.

DESCRIPTION

FIG. 1 is a front view of a beverage container package showing my new design.

FIG. 2 is a side view thereof;

FIG. 3 is a top view thereof;

FIG. 4 is a top side perspective view thereof; and,

FIG. 5 is a top side perspective view of an alternate embodiment of the beverage container package showing my new design, the only difference being the height of the package.

The back of the invention is a mirror image of the front, the second side is a mirror image of the first side, and the button is a mirror image of the top.

The broken line showing is for illustrative purposes only and form no part of the claimed design.
